UNITED STATES PATENT OFFICE.

FREDERICK W. HOCHSTETTER, OF NEW YORK, N. Y., ASSIGNOR TO PAUL M. PIERSON,
OF SCARBORO-ON-THE-HUDSON, NEW YORK.

RESTORATIVE FOR BLEMISHED MOVING-PICTURE FILMS.

1,139,679.

Specification of Letters Patent.

Patented May 18, 1915.

No Drawing.

Application filed November 20, 1912. Serial No. 732,465.

To all whom it may concern:

Be it known that I, FREDERICK W. HOCHSTETTER, a subject of the Emperor of Germany, and a resident of New York, county 5 and State of New York, have invented a new and useful Restorative for Blemished Moving-Picture Films, of which the following is a full, clear, and exact specification.

My invention has for its object to provide 10 a composition of matter designed to be employed for restoring the pictures upon the types of films ordinarily used in conjunction with moving picture machines when the pictures have become blemished by scratches, or 15 the clearness of the photography being bedimmed by fine particles of dust which the film invariably collects as it passes through the transmitting mechanism of the machine, thus causing what is commonly known as 20 "rain" in the pictures when projected upon a screen and which tends to make the pictures practically worthless after being used a limited number of times.

A preferred form of my composition of 25 matter consists of the following ingredients, combined in the proportions stated, viz:— petrodatum, 6 ounces; spirits of camphor, (U. S. P. strength) by weight 2 ounces; sulfuric ether, (U. S. P. strength) by 30 weight $\frac{1}{2}$ ounce; glycerin by weight 1 ounce.

The petrodatum is first melted by heat at a low temperature, and while the petrodatum is in a melted state the glycerin is mingled in any suitable manner. When this 35 mixture has become cool the spirits of camphor and the sulfuric ether, either separately, or after being previously mixed, are then added, and all of the ingredients are thoroughly incorporated together by agitation 40 through the employment of any desired methods so as to produce a smooth and uniform emulsion.

To use the composition for restoring the blemished pictures of a film a required 45 quantity of the emulsion to form a coating

is applied upon a surface of the film by the use of one, or more buffers made of chamois skin, flannel, or other soft material. By then thoroughly rubbing the coating on the film the emulsion will penetrate 50 the crevices of the scratches as well as softening the texture of the film for restoring its flexibility. By subsequently removing all excess of the emulsion from the film with the use of a pad, or otherwise, all the 55 scratches will be cleared of particles of the dust, or other foreign substances, and the clearness of the high lights and shadows of the photography of the pictures will also be renewed. 60

While in the foregoing description I have set forth the preferred formula of my composition, I do not wish to be understood as limiting myself thereto, as I am aware that the proportions of the ingredients mentioned may be varied as well as dispensing with the use in conjunction with an oil of one or more of other ingredients, without departing from the principle, or sacrificing any of the advantages of this invention, 70 therefore I reserve to myself the right to make such changes as fairly fall within the scope of the appended claims. 65

Having thus described my invention, I claim as new and desire to secure by Letters 75 Patent:—

1. A restorative for blemished moving picture films consisting of petrodatum, spirits of camphor, sulfuric ether, and glycerin, substantially as set forth. 80

2. A restorative for blemished moving picture films comprising petrodatum six ounces, spirits of camphor two ounces, sulfuric ether one-half ounce, and glycerin one ounce.

This specification signed and witnessed. 85

FREDERICK W. HOCHSTETTER.
